SLICING MACHINE

Willard B. Felton, Pueblo, Colo.

Application December 8, 1930, Serial No. 500,946

6 Claims. (Cl. 146—94)

The present invention relates generally to slicing machines, and more particularly to a machine for slicing bacon.

Sliced bacon as sold in boxes has the various slices arranged in partly overlapping relation, and in large plants where bacon is packed in boxes, it is necessary to employ a number of persons to arrange the slices in overlapping relation before placing them in boxes, a procedure which is not only expensive, but one requiring considerable time.

It is therefore the object of the present invention to provide a slicing machine wherein the severed strips or slices are automatically arranged in partly overlapping relation, so that the proper number of slices can be taken directly from the machine and quickly and conveniently arranged in boxes.

In this connection, the invention provides a horizontally disposed rotary cutter located immediately above a movable carrier, the movement of which is timed with relation to the cutter, so that the slices of material as they are cut are automatically arranged in partly overlapping relation on the carrier.

Another object of the invention resides in the novel construction of means whereby the thickness of the slices can be varied or regulated.

Another object of the invention resides in the provision of a machine of the character mentioned, wherein the material to be severed can be quickly placed in the machine, and supported in a novel manner.

The nature and advantages of the invention will be better understood when the following detailed description is read in connection with the accompanying drawings, the invention residing in the construction, combination and arrangement of parts as claimed.

In the drawings forming part of this application like numerals of reference indicate similar parts in the several views and wherein:

Figure 1 is a side elevation of the machine.

Figure 2 is a top plan view.

Figure 3 is a sectional view on line 3—3 of Figure 1.

Figure 4 is a sectional view on line 4—4 of Figure 2.

Figure 5 is an enlarged fragmentary sectional view showing how the slices are automatically arranged in partly overlapped relation upon the carrier.

Figure 6 is a fragmentary view of the carrier showing the driving connection therefor.

The frame of the machine comprises spaced

upper and lower plates 10 and 11 respectively which are connected together by suitable standards 12, while the frame in its entirety is supported by suitable legs 13. Arranged centrally between the plates 10 and 11 and journaled in suitable bearings 14 is a shaft 15 which projects beneath the lower plate 11 and carries a rotatable horizontally disposed cutter or blade 16. The cutter 16 is preferably of the configuration or outline illustrated by dotted lines in Figure 3, and operates directly beneath the lower plate 11 of the frame, and across an opening 17 provided in the bottom plate 11 at one side of the shaft 15 as clearly illustrated in Figure 5. The material to be sliced is supported in a manner to be hereinafter described, between the plates 10 and 11 and is fed through the opening 17, and is severed in slices incident to the rotation of the cutter 16.

The means for supporting the material to be sliced includes a substantially L-shaped guide plate 18 clearly illustrated in Figures 3 and 5, and which plate is arranged at an angle transversely of the upper and lower plates 10 and 11 of the frame to which the guide plate 18 is secured. For this purpose the guide plate 18 is flanged as at 19, these flanges engaging the adjacent plates 10 and 11 of the frame to which they are secured by suitable fastening elements 20. The supporting means also includes an arm 21 which extends transversely across the guide plate 18, and more clearly illustrated in Figure 3. The arm 21 is formed with an offset ear 22 at one end, and carries a similar ear 23 adjacent its opposite end, and between which ears is pivotally mounted a clamping plate 24. One edge of the plate 24 is rolled upon itself to receive a pivot rod 25 supported by the ears 22 and 23 of the arm 21, so that the plate can be swung upon the pivot rod to either an active or inactive position. Projecting from one side of the clamping plate 24 is a transverse series of prongs 26, while arranged on the opposite side of the plate 24 is a vertical series of teeth 27 normally engaged by a pivoted pawl 28. The pawl 28 is pivoted from the ear 23 of the arm 21 as clearly shown in Figure 5. The arm 21 together with the clamping plate 24 is supported for sliding movement vertically on a feed screw 29, for which purpose the arm is provided with a sleeve-like portion 30 which surrounds the feed screw 29 as shown in Figure 1. The sleeve 30 is slotted at one side to receive a portion of a block 31, which portion is provided with threads to engage the threads of the feed screw 29. The block 31 includes a stem 32 which slides through a hole

low tubular member 33 carried by the sleeve 30, and which stem is provided with a collar 34 at an appropriate point in its length, and with a knob 35 at its free extremity. Surrounding the 5 stem 32 is a coiled spring 36, one end of which bears against the bottom of the tubular member 33 and its other end bearing against the collar 34, the spring exerting a pressure upon the stem to hold the block 31 effectively in engagement 10 with the feed screw 29.

From the construction thus far described, it will be manifest that the material to be sliced and indicated at 37' is clamped between the stationary 15 guide plate 18 in the pivoted clamping plate 24, the prongs 26 of the latter being embedded in the material 37' as clearly illustrated in Figure 5. The material 37' can be quickly and conveniently arranged in the machine, by releasing the 20 plate 24 from the pawl 28, and swinging the plate 24 outwardly upon its pivot. After the material has been arranged against the stationary 25 guide plate 18, the clamping plate and pawl 28 are arranged in the position illustrated in Figure 5. When the machine is in operation the feed 30 screw 29 is rotated in a manner to be hereinafter described, and incident to the rotation of this screw, the block 31 is fed longitudinally of the feed screw 29 together with the sleeve 30, and in this manner, the material is gradually fed through 35 the opening 17 in the lower plate 11, to be sliced by the rotation of the cutter 16. When the material has been completely sliced or substantially so, the arm 21 which has been previously lowered 40 incident to the feed of the material through the opening 17, can be quickly and easily elevated to its normal position, by simply pressing against the knob 35 of the stem 32 carrying the block 31, thereby disengaging the block 31 from the feed screw, and allowing the sleeve 30 together with 45 the arm 21 to be slid upwardly on the feed screw to the desired position. When the stem 32 is released, the spring 36 automatically moves the block into engagement with the feed screw so that the parts are arranged for further operation of the machine.

The machine is operated by means of an electric motor 37 mounted upon the upper plate of the frame, which motor includes a shaft 38 carrying a beveled pinion 39 which meshes with a beveled gear 40 secured to the upper end of the shaft 15. Also carried by the shaft 15 is a gear 41, while carried by the upper end of the feed screw 29 is a gear 42, which gears are operatively associated through the instrumentality of an intermediate gear 43. Obviously, the ratio of these gears regulates the speed with which the feed screw 29 is rotated, and consequently regulates the thickness of the slice to be cut from the material 37'. By changing the gear ratio, the thickness of the slices to be cut from the material 37' can therefore be varied, and obviously the thinner the slices are cut the closer they are stacked upon the carrier.

For this purpose any type of a change speed device can be employed, and interposed between the shaft 15 of the cutter and the feed screw 29 of the feeding mechanism. Such a device can be of the construction illustrated including the gears 42 and 43, which are capable of being transposed, so that the gear 42 can be associated 65 with the arm 44 and used as an idler, with the gear 43 associated with the feed screw 29. Obviously any suitable means can be employed, such as a set screw for holding the gear mounted on the feed screw 29 fixed relatively thereto. When 70 the larger gear 43 is attached to the feed screw

29, and a smaller gear used as an idler between the gears carried by the cutter shaft 15 and the feed screw 29, the material is cut into thinner slices, and the slices are stacked closer together on the carrier. Of course, while the gears 42 and 43 can be interposed as above stated, both of the gears can be separated from the machine and other gears of proper ratio used in their place. The particular change speed device employed may be of any conventional form to provide an operative connection between the shaft 15 of the cutter and the feed screw 29. The idler gear 43 is preferably supported on a slotted arm 44, one end of which is bifurcated to receive a hollow boss or bearing 45 rising from the uppermost plate 10 of the machine as clearly illustrated in Figure 4. The free ends of the bifurcated portion of the arm 44 are connected together and tightened about the boss 45 by a suitable bolt 46. Received by the slot 47 of the arm 44 is a bearing block 48 in which is threaded the lower end of a short shaft 49. This shaft projects above the block 48 and is passed through the hub 50 of the intermediate gear 43. The lower end of the block 48 is formed with a flange 51 which bears against the lower side of the arm 44, while interposed between the block 48 and the hub 50 is a washer 52. Manifestly, when the shaft 49 is tightened within the block 48, the intermediate gear 43 is held operatively associated with the 105 arm 44, but the gear can be easily and quickly replaced by removing the shaft 49 from the block 48 as will be readily understood. To transpose the gears 42 and 43 for the purpose above stated it is necessary to swing the arm 44 outwardly 110 away from the gears 41 and 42 respectively, for which purpose the arm 44 is pivoted upon the hollow boss 45. When the arm is in the position illustrated in Figure 2, with the intermediate gear operatively connecting the gears 41 and 42 respectively, the arm 44 is held stationary by tightening the bolt 46, but when it is desired to transpose said gears, the bolt 46 is loosened to permit the arm 44 to be swung to an inactive position upon the hollow boss 45 as a pivot. After 115 the gears 42 and 43 have been transposed, the arm 44 is returned to its normal active position, and the screw 46 tightened to hold the arm 44 fixed with relation to the adjacent plate 10 of the machine.

As each slice is cut from the material 37' it is laid upon a movable carrier which operates directly beneath the frame of the machine and also beneath the cutter 16 as clearly illustrated in Figure 5. While this carrier may vary in form, 130 it is preferably in the nature of an endless carrier indicated at 53 and trained over spaced rollers 54, one of which is journaled in suitable brackets 55 depending from the bottom of the lower plate 11, while the other is journaled in 135 suitable brackets 56 carried by an auxiliary frame or guide-like structure indicated generally at 57 and including supporting legs 58. The upper rung of the endless carrier also passes over suitable rollers 59 carried by the auxiliary guide or frame-like structure 57, while the lower rung of the endless carrier passes over similar rollers 60 clearly illustrated in Figure 1. The endless carrier may be made up of one piece or in several pieces or elements as illustrated, while the shaft 61 of one 140 of the rollers 54 is provided with a sprocket 62. Trained over this sprocket and a smaller sprocket 63 is an endless drive chain 64, whereby the endless carrier is operated simultaneously with the cutter 16. The small sprocket 63 is carried by a 145

shaft 65 equipped with a beveled gear 66 which meshes with a similar gear 67 carried by the lower end of the feed screw 29, so that incident to the rotation of the feed screw 29 the endless carrier 5 is operated.

One of the most important features of the present invention, resides in the novel arrangement of the parts, whereby the slices as they are cut from the material 37' are automatically laid 10 upon the carrier 53 in partly overlapped relation as clearly illustrated in Figure 5. While the machine possesses general utility as a slicing machine, it is primarily designed for the purpose of slicing bacon, and arranging the slices 15 automatically in overlapping relation upon the carrier 53, so that a predetermined number of slices can be quickly and conveniently arranged in a box for sale, and taken directly from the carrier 53 for this purpose. This is accomplished 20 by arranging the cutter 16 horizontally and directly above the adjacent end of the carrier 53, and imparting motion to both the cutter and carrier in such timed relation, that as each slice is severed from the material 37' it is laid upon 25 the previously severed slice in partly overlapping relation as shown in Figure 5. It will be manifest, that all moving parts of the machine are operated from the motor 37, the latter being directly geared to the cutter shaft 15, while the 30 feed screw 29 is simultaneously rotated through the train or gearing 41, 42 and 43 respectively, while the carrier is also driven or operated from the lower end of the feed screw 29.

While it is believed that from the foregoing description the nature and advantages of the invention will be readily understood, I desire to have it known that I do not limit myself to what is herein illustrated and described, and that such changes may be resorted to when desired, as fall 40 within the scope of what is claimed.

What I claim as new is:

1. In a slicing machine, a horizontal rotary cutter including a shaft, means for rotating the shaft, a feed screw mounted for rotation, a 45 change speed device interposed between said shaft and feed screw, means for supporting the material to be sliced, including a stationary guide plate, an arm arranged transversely thereof and in spaced relation thereto and slidably mounted 50 upon the feed screw, a plate carried by the arm for clamping said material between the plate and said stationary guide, means embodying said change speed device for rotating the feed screw from said shaft, means connecting the arm with 55 the feed screw whereby the arm is moved longitudinally of the feed screw to feed the material to said cutter, said cutter being of such shape that when rotated its cutting edge traverses the path of feed of the material, an endless carrier 60 movable beneath the cutter, and means for imparting motion to the carrier from the feed screw and in timed relation with the cutter, whereby the slices as they are cut are automatically arranged in partly overlapping relation upon the 65 carrier.

2. In a slicing machine, a frame including spaced upper and lower plates, said lower plate having an opening therein, a vertical shaft journaled between said plates, a horizontal rotary 70 cutter carried by the shaft and operating beneath the lowermost plate and across said opening, a feed screw operated from said shaft, means for supporting the material to be sliced, including a stationary guide plate located between the 75 plates of said frame, an arm arranged trans-

versely of the guide plate and supported by the feed screw for movement longitudinally thereof, incident to the rotation of said screw, a pivoted clamping plate carried by the arm for clamping the material between the plate and said guide, means for holding the clamping plate in its active position, an endless carrier operating beneath the cutter, and means for imparting motion to the carrier from the feed screw, and in timed relation with the cutter, whereby the slices as they are cut are automatically arranged in partly overlapping relation upon the carrier. 80

3. In a slicing machine, a horizontal rotary cutter, including a vertically disposed shaft mounted for rotation, means for rotating said shaft, a feed screw mounted for rotation and operated from said shaft, means for supporting the material to be sliced including an arm slidably mounted upon the feed screw, a yieldably supported block carried by the arm and normally having threaded engagement with the feed screw, whereby the arm is moved downwardly on the feed screw incident to the rotation thereof, means for separating the block from the screw to permit the arm to be elevated upon the feed screw, an 100 endless carrier located beneath the cutter, and means for imparting motion to the carrier from the feed screw, and in timed relation with the cutter, whereby the slices as they are cut are automatically arranged in partly overlapping relation upon the carrier. 105

4. The combination with means for automatically cutting horizontal slices from the bottom of a vertically disposed piece of bacon at predetermined intervals, of a horizontal carrier arranged directly beneath said cutting means so that the slices will fall flatwise directly thereon as they are cut, means to horizontally move said carrier in timed relation to the slicing means so that the carrier receives the slices in uniform 115 overlapping relation, said cutting means including a power operated cutter and means for automatically feeding the bacon downwardly to the cutter at a predetermined speed, and means for changing the speed of movement of said carrier 120 and the speed of operation of said feeding means relative to the speed of operation of said cutter to vary the thickness and the amount of overlap of the slices. 115

5. The combination with means for automatically cutting horizontal slices from the bottom of a vertically disposed piece of bacon at predetermined intervals, of a horizontal carrier arranged directly beneath said cutting means so that the slices will fall flatwise directly thereon 130 as they are cut, means to horizontally move said carrier in timed relation to the slicing means so that the carrier receives the slices in uniform overlapping relation, said cutting means including a cutter and means including a feed screw 135 for feeding the bacon downwardly to the cutter at a predetermined speed, and means for changing the speed of movement of said carrier and the speed of operation of said feeding means relative to the speed of operation of said cutter 140 to vary the thickness and the amount of overlap of the slices, said carrier moving means including a driving connection between said carrier and said feed screw. 140

6. The combination with means for automatically cutting horizontal slices from the bottom of a vertically disposed piece of bacon at predetermined intervals, of a horizontal carrier arranged directly beneath said cutting means so that the slices will fall flatwise directly thereon 150

as they are cut, means to horizontally move said carrier in timed relation to the slicing means so that the carrier receives the slices in uniform overlapping relation, said cutting means including a cutter and means including a feed screw for feeding the bacon downwardly to the cutter at a predetermined speed, and means for changing the speed of movement of said carrier and the speed of operation of said feeding means

relative to the speed of operation of said cutter to vary the thickness and the amount of overlap of the slices, said carrier moving means including a driving connection between said carrier and said feed screw, means for driving said cutter, and a driving connection between said cutter and said feed screw embodying said speed changing means.
